SLIDE FASTENER AND CONCEALING MEANS THEREFOR

Filed Feb. 2, 1932

INVENTOR
Samuel Lacher,
BY George D. Lach
ATTORNEY

UNITED STATES PATENT OFFICE

SAMUEL LACHER, OF NEW YORK, N. Y.

SLIDE FASTENER AND CONCEALING MEANS THEREFOR

Application filed February 2, 1932. Serial No. 590,340.

- This invention relates, generally, to slide fasteners of the type wherein cooperating edges of a bag, garment, curtain, tent or other article, are adapted to be connected by a fastener which embodies interlocking elements provided on the edges of the article and arranged to be engaged and disengaged by a sliding operating device or slider; the interlocking elements constituting means for closing the edges when the slider is moved in one direction and then permitting the edges to open when the slider is moved in the opposite direction; and the invention has reference, more particularly, to a novel improvement in slide fasteners of this character, said improvement embodying the use of means for concealing the interlocking members and the body portion of the slider.
- Heretofore, in using slide fasteners of this character, the interlocking elements together with the slider are commonly exposed on the exterior surface of the bag or other means adapted to be closed and opened by the fastener. This exposure of the fastener is objectionable, not only because the same is not particularly attractive, but especially because water and other foreign matter tends to collect on the interlocking elements and to work in between these elements, thereby interfering with the proper movement of the slider over these elements and in time so reducing their efficiency that the same cannot be depended upon to serve their closure function. The exposure of these fasteners is particularly objectionable in cold weather, at which time moisture collecting upon the fastener, tends to freeze on the same, thereby rendering the operation of the fastener difficult or at times impossible. Thus, when these fasteners are used on skating garments, ice collecting in the interlocking elements of the fastener, hinders or even prevents operation of the slider.
- The principal object of the present invention is to provide an improved slide fastener and concealing means therefor, which concealing means is adapted to substantially conceal the fastener, thereby protecting the same against the elements and against foreign ma-
- terial, while at the same time, said concealing means presents an extremely attractive appearance and prevents the rather unattractive interlocking elements of the fastener from being seen.
- Another object of the present invention lies in the provision of a novel improved slide fastener having a slider provided with an operating handle which is connected to the body portion of the slider by a plow member projecting between the opposed edges of the concealing means, said plow member being designed so as to move along between the opposed edges of the concealing means with a minimum of friction, thereby permitting the slider to be moved easily along in use.
- Another object of the present invention is to provide an improved slide fastener and concealing means therefor, which concealing means consists of flaps or strip edge portions disposed in meeting relation and overlying the interlocking elements of the slide fastener, the said flaps or edge portions being formed with recesses at the limits of travel of the slider for accommodating the plow member of the slider.
- Other objects of this invention, not at this time more particularly enumerated, will be clearly understood from the following detailed description of the same.
- The invention is clearly illustrated in the accompanying drawing, in which:
- Fig. 1 is a plan view of a cylindrical frameless bag provided with the novel slide fastener and concealing means of this invention.
- Fig. 2 is an enlarged fragmentary view of a portion of the structure shown in Fig. 1 and illustrates the slider in operation.
- Fig. 3 is a fragmentary, sectional view taken substantially along line 3—3 of Fig. 2 looking in the direction of the arrows.
- Fig. 4 is a fragmentary, sectional view taken substantially along line 4—4 of Fig. 2 looking in the direction of the arrows.
- Fig. 5 is a part sectional view taken substantially along line 5—5 of Fig. 2, looking in the direction of the arrows.
- Fig. 6 is a fragmentary, sectional view taken substantially along line 6—6 of Fig. 2 looking in the direction of the arrows; and

Fig. 7 is a view similar to Fig. 6 but illustrates a somewhat modified form of construction.

Similar characters of reference are employed in all of the above described views, to indicate corresponding parts.

Referring now to Figs. 1 to 6 of the drawing, the novel slide fastener and concealing means therefor of this invention is illustrated 10 as applied to a bag of the frameless type. It is to be understood, however, that the present invention is equally applicable to other types of bags or grips and to all articles employing slide fasteners, such as garments, curtains, 15 tents and the like. The reference numeral 1 designates the bag as a whole, which bag may be made of any suitable flexible material, such as leather or textile fabric. The bag 1 is formed adjacent its opening with meeting 20 cover portions or flies 2, 2. Tapes or stringers 3, 3 underlie the cover portions or flies 2, 2 and are sewn to the bag or other body by longitudinal rows of stitching 6, 6 that are spaced rearwardly from the meeting edges 7 25 of the cover portions or flies 2, 2. The opposed edges of the tapes 3, 3 have interlocking elements 4, 4 clamped thereon in staggered relation.

A manipulating slider has a hollow Y-shaped body portion 5 which fits over interlocking elements 4 and is adapted to travel along the tapes 3, 3 for engaging and disengaging the interlocking elements 4. The body portion 5 has slotted sides through 35 which the stringers or tapes 3, 3 extend laterally, to dispose the members 4 in operative relation to the body portion 5. The cover portions or flies 2 of the bag 1 extend into overlying relation to the tapes 3 and the interlocking elements 4, and the abutting edges 7 of these cover portions or flies substantially overlie the longitudinal central portion of the fastener means as a whole.

The slider body portion 5 is formed with 45 an upward projection or plow member 8 for receiving the operating handle or tug of the slider, and said plow member projects outwardly between the opposed edges 7 of the cover portions or flies 2. The plow member 8 is made relatively narrow as compared with its length so that this member may slide along between the opposed edges 7 of the cover portions or flies with a minimum of 55 friction. Plow member 8 has pointed or wedge-shaped ends 9 to facilitate the movement of this plow member along and between the abutting edges 7 of the cover portions or flies 2. Plow member 8 is preferably formed 60 with slots 10 in its sides for receiving inverted projections formed on the slider handle or tug 11, which slots are positioned above the cover portions or flies 2, and exteriorly of the bag 1. By grasping the handle or 65 tug 11, the plow member and hence the body

portion 5 of the slider may be moved in either direction along the length of the bag.

The opposed cover portions or flies 2 are recessed or indented somewhat at the limits of travel of the slider so as to provide openings 12 for conformably receiving the plow member 8 of the slider on completion of its strokes. With the slider at one end of its travel, as shown in Fig. 1, the plow member 8 projects upwardly through one of the openings 12, and the opposed edges 7 of the cover or flies 2 of the bag lie in abutting relation all along the length of the bag, thereby completely covering the underlying interlocking elements 4 in protecting relation thereto, 75 while at the same time causing the bag to have a neater and more attractive appearance. 80

In use, if it be assumed that the bag is in closed position, as shown in Fig. 1, and it is desired to open the bag, it is merely necessary to grasp the handle or tug 11 and pull the slider towards the right, as especially shown in Fig. 2. As the slider commences to move toward the right, the body portion 5 90 commences to disengage the interlocking elements 4 while the advancing narrow plow member 8, owing to the pointed or wedge nature of this member, moves readily between the meeting edges 7 of the cover portions or flies 2, so that the slider moves along with ease. 95

In Fig. 3, the cover portions or flies 2 of the bag are just beginning to separate owing to the approach of the plow member 8, and in Fig. 5 the body portion of the slider is shown separating the interlocking elements 4 while the plow member 8 passes along between the opposed edges 7 of the cover portions or flies 2. In Fig. 4 the slider is shown 105 as having passed the point at which this section was taken, and effected the complete disengagement of the bag edge portions rearwardly of the slider. Since the handle or tug 11 is positioned above the cover portions or flies 2 of the bag, these cover portions or flies do not interfere with the manipulation of this handle. When the slider has reached the end of its travel, the plow member 8 enters the other terminal opening 12, thereby 115 effecting the completion of the disengagement of the edge portions of the bag opening. 120

It will be apparent that instead of said cover portions or flies 2 forming an integral part of the bag or other body the same may be provided in the form of separate strips 13, suitably attached to the bag or other body, as, for example, by the stitching 14; this arrangement being shown in Fig. 7 of the drawing. 125

As many changes could be made in the above construction and many apparently widely different embodiments of this invention could be made without departing from the scope thereof, as defined by the following 130

claims, it is intended that all matter contained in the above description or shown in the accompanying drawing shall be interpreted as illustrative and not in a limiting sense.

What is claimed is:

1. The combination with the opposed edge portions of an article, said edge portions normally lying in a common plane and having abutting edges, of a slide fastener for connecting said article edge portions, said slide fastener comprising opposed tapes attached respectively to said respective edge portions rearwardly of the margins thereof, said tapes having cooperable interlocking elements, said tapes and said interlocking elements being substantially hidden and protected by said edge portions, and a slider movable along said tapes for effecting the engagement and disengagement of said interlocking elements, said slider having a plow projection extending outwardly between said edge portions, said plow projection being relatively narrow and having pointed ends to facilitate the easy movement of the same between said edge portions and an operating handle attached to said plow projection exteriorly of said edge portions.

2. The combination with two separable parts of an article, said parts having flies, of a slide fastener for connecting said article parts, said slide fastener comprising, tapes attached to said parts, cooperable interlocking elements attached to said tapes, said tapes and said interlocking elements being covered and protected by said flies, and a slider having a body portion movable along said tapes for effecting the engagement and disengagement of said interlocking elements, a plow projection provided on said body portion, said plow projection extending outwardly between said flies and having a tug attached thereto exteriorly of said flies, said flies being indented at the limits of travel of said slider to provide recesses for conformably receiving said plow projection.

3. The combination with the opposed edge portions of an article, said edge portions being positioned to lie in a common plane and having adjoining, abutting edges, of a slide fastener for connecting said article edge portions, said slide fastener comprising opposed tapes sewn respectively to said respective edge portions, said tapes having cooperable interlocking elements, said tapes and said interlocking elements being substantially hidden and protected by said edge portions, and a slider having a body portion movable along said tapes for effecting the engagement and disengagement of said interlocking elements, said slider having a plow projection extending outwardly from said body portion and lying between said article edge portions, and an operating handle attached to said plow projection exteriorly of said edge por-

tions, said edge portions having recesses in their abutting edges at the limits of travel of said slider for conformably receiving said plow projection.

In testimony, that I claim the invention set forth above I have hereunto set my hand this 29th day of January, 1932.

SAMUEL LACHER.
